UNITED STATES PATENT OFFICE.

JAMES G. WARNER, OF WEST UNION, WEST VIRGINIA.

TOOL FOR SLITTING CASINGS.

1,418,757.

Specification of Letters Patent. Patented June 6, 1922.

Application filed September 20, 1921. Serial No. 502,941.

To all whom it may concern:

Be it known that I, JAMES G. WARNER, a citizen of the United States, residing at West Union, in the county of Doddridge and 5 State of West Virginia, have invented a new and useful Tool for Slitting Casings, of which the following is a specification.

This invention relates to a tool designed primarily for slitting well casings where 10 they are connected to the couplings so that should a casing become hung within a well, it becomes possible by slitting the casing in one of the couplings above the point where the casing is held, to withdraw that portion of 15 the casing above the slit portion.

A further object is to provide a tool of this character which can be adjusted so as to form slits in casings of different thicknesses without mutilating, to an objectionable extent, the threads in the collar into 20 which the casing extends.

A further object is to provide a tool which, when connected to jars can be hammered upwardly into the lower end of the casing engaged thereby so as to plough through the metal and allow the threaded end to contract and thus become disengaged from the 25 threaded collar.

A further object is to provide means 30 whereby the cutting members can be automatically locked in inactive or retracted positions after the completion of the cutting operation, thus to permit the tool to be withdrawn readily from the casing.

With the foregoing and other objects in view which will appear as the description proceeds, the invention resides in the combination and arrangement of parts and in the details of construction hereinafter described 35 and claimed, it being understood that, within the scope of what is claimed, changes in the precise embodiment of the invention shown can be made without departing from the spirit of the invention.

40 In the accompanying drawings the preferred form of the invention has been shown.

In said drawings

Figure 1 is a side elevation of the tool showing the parts set for insertion into a 50 casing.

Figure 2 is a section on line 2—2, Figure 1 showing the tool in a casing.

Figure 3 is a section on line 3—3, Figure 2.

Figure 4 is a section on line 4—4, Figure 2.

55 Referring to the figures by characters of

reference 1 designates the body of the tool having a tapered threaded coupling stem 2 at one end while extending from its other end is a cylindrical stem 3 the free end portion of which is screw threaded as shown at 4 and is provided with a longitudinal slot 5. On this stem is slidably mounted a collar 6 and a spring 7, which surrounds the stem 3, serves to hold the collar normally pressed against a shoulder 8 formed at the upper end of the stem. This spring bears at one end against the collar and at its other end extends into a counterbore 9 formed in a cap 10 which is screwed onto the threaded portion of the stem 3 and has its free end rounded to a point 11. A threaded bore 12 extends into the cap for the reception of the stem 3 and by turning the cap on the stem it can thus be adjusted longitudinally thereof. After the cap has been brought to a desired 70 position a pin or key 13 can be inserted therethrough and through the slot 5. A latch 14 is pivotally mounted in a groove 15 formed longitudinally in the stem 3 and a spring 16 serves to hold the latch normally projected at one end so as to fasten the collar 6 against the shoulder 8.

75 Diametrically opposed portions of the body 1 are cut away to form upwardly converging flat faces 17 extending from the shoulder 8. Each of these faces is provided with a longitudinal dove-tailed groove 18. Mounted on each face is a jaw 19 having a longitudinally extending dove-tail 20 adapted to slide within the adjacent groove 18.

80 A dove-tailed groove 21 is extended downwardly into the outer face of each jaw 19 from the upper end thereof and is adapted to receive a dove-tailed block 22 constituting a cutter and provided with an outstanding portion 23 formed with a cutting edge 24. Rivets 25 or the like can be extended through the upper ends of these blocks and into the jaws 19 so as to hold the cutters against accidental separation from the jaws. It will be noted that the blocks completely 85 fill the dove-tail grooves and bear downwardly against the lower end walls of the grooves as shown in Figure 2.

90 Under normal conditions the collar 6 is pressed against the shoulder 8 by spring 7 where it is fastened by the latch 14. Thus the jaws 19 are pressed against the shoulders 26 formed at the upper ends of the inclined faces 17 and the cutting edges 24 on the 95 100 105 110

opposed cutters are spaced apart a distance slightly less than the internal diameter of the casing C to be cut. In other words the diameter through the cutting portions of 5 the cutters is substantially equal to or slightly less than the greatest diameter of the body 1.

When it is desired to remove a section of casing the collar 6 is drawn downwardly 10 against the action of spring 7 after the latch 14 has been pressed inwardly. It is preferred to adjust the cap 10 on the stem 3 prior to this operation so as to permit only a predetermined movement of the collar. 15 After the collar has been moved downwardly against the cap slender sticks of wood or the like indicated at 27 can be inserted between the collar and the shoulder 8. The jaws 19 will gravitate so as to rest on the collar 20 and as the faces 17 are inclined the jaws will be moved apart so as to project the cutting edges laterally a distance equal to the thickness of the wall of the casing to be cut. The tool is attached to jars of ordinary construction and is then lowered into the casing. 25 The drag of the cutting blocks on the inner surface of the casing will be sufficient to keep the jaws 19 close to the shoulders 26 during the descent of the tool. 30 When the tool is brought to a level close to but above the point where it is desired to disconnect the casing sections it is pulled upwardly slowly so that when the cutting edges 24 arrive opposite the space between 35 the casing sections C and within the coupling C' they will move outward by the gravitation of the jaws 19 on the inclined faces 17. Thus the cutting blocks will be brought to the positions shown in Figure 2. By now 40 moving the jars upwardly the tool can be subjected to successive upward impacts or hammering strokes with the result that the cutting edges 24 will plough into the lower edge of the casing section thereabove and 45 will slit said section longitudinally to a point above the coupling.

By now reversing the stroke of the jars the tool can be driven downwardly abruptly, the force being sufficient to crush or break 50 the spacing pieces 27 and allow the shoulders 8 to move downwardly against the collar 6 whereupon the latch 14 will fasten the collar. Thus the jaws 19 will be held against the shoulders 26 and the cutting edges 24 55 will be held retracted from the slits produced thereby. Consequently the tool can be raised readily from the casing. By then pulling upwardly on the casing the slotted portion thereof will contact out of engagement with the threads in that portion of the collar surrounding the same and the casing can thus be pulled upwardly out of the well, leaving that portion located below the coupling from which the withdrawn casing 60 was removed.

It is to be understood that the tool can be made of different sizes so as to work within casings of different sizes. Instead of providing the tool with two flat faces and a sliding jaw on each face, it can be provided with three, four or more faces each carrying a sliding jaw on which is located a cutter. 70

It will be noted that the cutters are removable so that new ones can be placed in 75 position in event of excessive wear or breakage.

Ordinarily the spacing members 27 will be released and will fall from their positions when the cutting devices are brought 80 against the lower end of the casing to be slit but it is desirable to make the spacing devices of wood or other frangible material so that they can be easily crushed or broken should they fail to become unseated. 85

What is claimed is:

1. The combination with a body having upwardly converging faces, of jaws slidably mounted on said faces, cutting members carried by the jaws, yieldingly supported means 90 for holding the jaws normally elevated with the cutting members retracted toward each other, and frangible means insertible between said means and the body for releasing the jaws to gravitate and shift the cutting members radially from each other. 95

2. The combination with a body having converging faces, a stem, and a cap adjustable upon the stem, of a collar slidable on the stem, and limited in its movement in opposite directions by the body and cap respectively, yielding means for holding the collar normally positioned against the body, means for automatically fastening the collar in normal position, jaws slidably mounted on the converging faces, said jaws being held normally against movement by the collar, and cutting means upon the jaws. 100 105

3. The combination with a body, converging faces thereon, a stem, and a cap adjustably mounted on the stem, of jaws slidably mounted on the faces, a yieldingly held collar upon the stem for holding the jaws normally raised, cutting members upon the jaws normally retracted toward each other, 115 and a latch for automatically fastening the collar in normal position, said collar being shiftable against the cap to receive a frangible spacing element between the collar and body, said jaws being adapted to gravitate 120 against the collar when spaced from the body, thereby to shift the cutting members radially from each other.

4. The combination with a body having upwardly converging faces and a stem, of a 125 cap adjustably mounted on the stem, a yieldingly held collar slidable on the stem between the body and cap, and normally pressed against the body, a latch for automatically fastening the collar against the 130

body, jaws slidable upon the converging faces and supported by the collar, and detachable cutting members upon the jaws, said collar being shiftable against the cap 5 for the reception of a frangible spacing element between the collar and the body.

In testimony that I claim the foregoing as

my own, I have hereto affixed my signature in the presence of two witnesses.

JAMES G. WARNER.
